UNITED STATES PATENT OFFICE.

OSWALD H. HANSEN, OF PORT WASHINGTON, WISCONSIN, ASSIGNOR TO UNITED PHONOGRAHS CORPORATION, OF SHEBOYGAN, WISCONSIN.

PHONOGRAPH-STOP.

1,285,140.

Specification of Letters Patent. Patented Nov. 19, 1918.

Application filed June 12, 1917. Serial No. 174,184.

To all whom it may concern:

Be it known that OSWALD H. HANSEN, a citizen of the United States, residing at Port Washington, in the county of Ozaukee and State of Wisconsin, has invented a certain new and useful Improvement in Phonograph-Stops, of which the following is a specification.

This invention relates to improvements in the construction of controlling devices for sound reproducing machines, and has particular relation to improvements in automatic stops for phonographs.

An object of the invention is to provide an automatic phonograph stopping device which is simple in construction and efficient in operation. Another object is to provide a stopping mechanism which is readily manipulable and which will operate to automatically stop the machine at a predetermined time. Still another object is to provide an automatic stop which may be readily manufactured and which will cooperate with any of the standard sound reproducing machines. A further object is to provide a phonograph stopping device or brake which may be released at but one place in order to start the machine, but which may be set at several places in order to stop the machine. Another object is to provide a tone arm actuated automatic stop mechanism in which suspension of elements constituting part of the mechanism, from the tone arm, is avoided.

A clear conception of an embodiment of the invention may be had by referring to the drawing accompanying and forming a part of this specification, in which like reference characters designate the same parts in the several views.

Figure 1 is a top view of a sound reproducing machine and an automatic stop, showing the brake set.

Fig. 2 is a top view of a sound reproducing machine and an automatic stop, showing the brake released.

Fig. 3 is a transverse fragmentary vertical section through a phonograph cover and stop supporting bracket, showing details of construction of several elements of the stop mechanism, the section being taken along the line III—III of Fig. 1.

The sound reproducing machine or pho-

nograph to which the automatic stopping device is herein disclosed as applied comprises, a cover 10, a circular horizontal record support 11 rotatable about a central vertical spindle 12 and having a peripheral cylindrical downwardly depending rim 28, a spring or electric motor of usual construction (not shown) located below the cover 10 and adapted to rotate the support 11, a tone arm 18 swingable to and fro above the record support 11 about a vertical axis located at the rear of the machine adjacent the periphery of the support 11, and a reproducer 29 having a needle coöperable with the spiral thread of a disk record 20 placed upon the record support 11.

The automatic stopping mechanism comprises a bracket 13, a brake 16, a latch 22, an operating lever 14, a trip arm 19, and an indicator arm 15. These elements are preferably formed of sheet metal with the use of dies, and are ordinarily finished by polishing or nickel plating.

The bracket 13 is detachably secured to the machine cover 10 by means of screws or other fastening means, and forms a mounting for the other elements of the stop mechanism.

The brake 16 is pivotally mounted upon the bracket 13 adjacent the tone arm axis, and has a pliable shoe 32 which is engageable with the interior of the rim 28 of the support 11, as shown in Fig. 1. A helical tension spring 17 connecting the brake 16 and bracket 13, normally urges the brake shoe 32 toward the rim 28. The brake 16 is provided with an elongated opening having a latch moving surface 24 at one portion thereof, and having an abutment 26 at another portion thereof. An upwardly extending projection 27 forms a second abutment on the brake 16.

The latch 22 is mounted to swing upon the bracket 13 about a pivot 23 which adjustably frictionally clamps the latch against the trip and indicator arms 19, 15. The upwardly extending projection 25 of the latch 22 projects through the opening in the brake 16 and is adapted to successively engage the brake surface 24 and the abutment 26.

The operating element or lever 14 has a central pivot 30 upon the bracket 13, and

has a readily accessible manipulating handle 35 located adjacent the periphery of the record support 11 at the front of the machine. The rear end of the lever 14 projects over the brake 16 and is movable into engagement with the latch projection 25 and with the brake projection 27.

The trip arm 19 is mounted to swing upon the bracket 13 about the pivot 23 which 10 adjustably frictionally clamps the trip arm against the latch 22. The trip arm 19 has an upwardly extending integral projection 33 provided with a pliable shoe which is engageable with the tone arm 18.

15 The indicator arm 15 is formed integral with the trip arm 19 and has a pointer adjacent its end which is movable over a graduated plate 21 mounted upon the cover 10. The arm 15 may be moved to any desired 20 position relatively to the plate 21, by means of a suitable handle 34. The frictional engagement between the arms 15, 19 and the latch 22, produced by the pivot 23, allows 25 adjustment of the arm 15 relatively to the plate 21 without necessarily displacing the latch 22.

In operating the device, it is at first desirable to ascertain just when the tone arm 18 should engage the trip arm 19, in order to 30 automatically stop the machine when the record 20 has been completely reproduced. This may be accomplished by placing a record 20 upon the record support 11 and locating the reproducer needle at or near the 35 end of the record thread. As practically all standard records have several revolutions at the thread end, entirely free from sound reproducing undulations, it is not necessary to stop the machine at the exact moment the 40 end of the thread is reached by the needle. The trip arm 19 may then be brought into engagement with the tone arm 18 as indicated in Fig. 1, by manipulating the indicator arm 15, the frictional connection be- 45 tween the latch 22 and the arms 15, 19 permitting relative movement of these elements. The record 20 may then be marked on its face or otherwise, with a number corresponding to the number on the graduated 50 plate 21, with which the pointer registered when the trip arm shoe just engaged the tone arm 18.

When it is desired to play the record thus marked and to utilize the automatic stop, 55 the record 20 is placed upon the record support 11 and the indicator arm 15 adjusted to point at the numeral on the plate 21 corresponding with that upon the record 20. The operating lever 14 is then swung in a 60 clockwise direction about its pivot 30, as viewed in Fig. 1, and engages the projection 27 of the brake 16. This engagement of the projection 27 swings the brake 16 in an anti-clockwise direction about its pivot, 65 thereby withdrawing the brake shoe 32 from

the rim 28. As the brake 16 swings in an anti-clockwise direction, the relative movement of the brake 16 and latch 22 causes the projection 25 of the latch to advance along the brake opening and to eventually strike 70 the surface 24. The inclination of this surface 24 causes the latch 22 and arms 15, 19 which are frictionally engaged thereby, to swing a slight amount in a clockwise direction as indicated in Fig. 2. Upon releasing 75 the lever 14, the spring 17 swings the brake 16 slightly in a clockwise direction causing the brake abutment 26 to engage the latch projection 25 and to hold the brake 16 in released position.

The driving motor is then free to rotate the record support 11 and record 20. The reproducer needle may then be placed upon the beginning of the record thread, and this thread being a spiral in form automatically 85 causes the tone arm 18 and reproducer 29 to move in a clockwise direction about the tone arm axis, as the record 20 rotates. When the reproducer needle approaches the end of the record thread, the tone arm 18 engages 90 the shoe of the trip arm 19 and gradually moves the trip arm 19, indicator arm 15 and latch 22, about the pivot 23 in an anti-clockwise direction. This motion of the latch 22 gradually slides the latch projection 25 95 along the brake abutment 26, returning the indicator arm 15 toward its initial position. As the arm 15 assumes its initial position the latch projection 25 is pushed off of the abutment 26, and the spring 17 becomes effective 100 to quickly move the brake 16 in a clockwise direction and to bring the brake shoe 32 into engagement with the rim 28, thereby stopping the machine.

When it is desired to manipulate the 105 brake manually and without utilizing the automatic stop, the brake 16 should first be set after which the trip and indicating arms 19, 15 should be swung in an anti-clockwise direction to such an extent that the tone arm 110 18 will not engage the projection 33 of the trip arm 19. The brake 16 may then be manually released by swinging the operating lever 14 in a clockwise direction. After release, the brake 16 may be set manually 115 by swinging the operating lever 14 in an anti-clockwise direction until the rear end of the lever engages the projection 25 of the latch 22 and pushes this projection off of the abutment 26, whereupon the spring 17 120 will immediately become effective to move the brake shoe 32 into engagement with the rim 28.

The brake 16 may also be set by manually 125 swinging the indicator arm 15 in an anti-clockwise direction about its pivot 23, this movement of the arm 15 simultaneously swinging the latch 22 in an anti-clockwise direction and causing the latch projection 25 to slide along and off of the brake abut- 130

ment 26. It will thus be noted that while the brake 16 may be released to start the machine, only by operating the lever 14, the brake may be set to stop the machine at 5 three places, namely, at the operating lever 14, at the trip arm 19 and at the indicator arm 15.

By locating the brake 16 near the tone arm pivot, the radial distance between the trip 10 arm shoe and the pivot 23, and the length of the latch 22, may be reduced to a minimum. With this construction, due to the relatively short radii, the projection 25 will be moved a sufficient distance to produce dis- 15 engagement between the latch projection 25 and the brake abutment 26, upon very slight angular displacement of the trip arm 19, thus producing a quick acting sensitive automatic stop. The location of the manually 20 manipulable end of the operating lever 14 at the front of the machine, provides for easy manual actuation of the mechanism.

The various elements of the stopping mechanism may be readily manufactured 25 from sheet metal with the use of dies at a very low cost. As none of the elements of the stopping mechanism require attachment to any of the phonograph parts other than the cover 10, the mechanism may be readily 30 applied to any of the standard disk types of sound reproducing machines. All of the essential elements of the stopping mechanism being mounted upon the bracket 13, makes it possible to exploit the device in 35 assembled condition ready for attachment to the phonograph.

It should be understood that it is not desired to be limited to the exact details of construction herein shown and described, 40 for various modifications within the scope of the appended claims may occur to persons skilled in the art.

It is claimed and desired to secure by Letters Patent:

- 45 1. In combination, a movable element, a brake for said element, means for setting said brake, latch means for holding said brake in release position, means movable in one direction to release said latch means to permit operation of said setting means and movable in the reverse direction to effect release of said brake, a trip arm for releasing said latch means, and an indicator arm for releasing said latch means.
- 50 2. In combination, a rotary element, a brake for said element, means for setting said brake, a latch for holding said brake in release position, manually operable means movable in one direction to release said latch to permit operation of said setting means and movable in the reverse direction to move said brake to release position, a trip arm for releasing said latch, and an indicator arm for releasing said latch.
- 55 3. In combination, a rotary element, a

brake for said element, a spring for setting said brake, a latch for holding said brake in release position, an operating lever movable in one direction to release said latch to permit operation of said spring and movable in the reverse direction to move said brake to release position, a trip arm for releasing said latch, and an indicator arm for releasing said latch. 70

4. In combination, a brake having a plurality of abutments, a latch having a projection engageable with one of said abutments to hold said brake in released position, said brake having a surface formed to engage and move said latch projection into said engaging position upon movement of said brake, to released position and an operating lever engageable with another of said brake abutments to move said brake and said latch into said engaging position, said lever also being engageable with said latch projection to disengage said latch from said brake abutment. 75

5. In combination, a brake having a plurality of abutments, a latch having a projection engageable with one of said abutments to hold said brake in released position, said brake having a surface formed to engage and move said latch projection into said engaging position upon movement of said brake to released position, an operating lever engageable with another of said brake abutments to move said brake and said latch into said engaging position, said lever also being engageable with said latch projection to disengage said latch from said brake abutment, and means for automatically disengaging said latch from said brake abutment at a predetermined time. 90

6. In combination, a rotary element, a 105 brake for said element, a latch for holding said brake in released position, a manually operable lever coöperable directly with said brake to release the same and alternately coöperable with said latch to permit setting of said brake, a trip arm automatically coöperable with said latch to permit setting of said brake, and an indicator arm coöperable with said latch to permit setting of said brake. 110

7. In combination, a brake, a latch engageable with said brake to hold the same in released position, means for automatically placing said latch into brake engaging position upon release of said brake, a manually 120 operable lever engageable with said brake to move the same into released position and engageable with said latch to disengage said latch from said brake, and other means for automatically disengaging said latch from said brake at a predetermined time. 125

8. In combination, a brake having a plurality of abutments, a latch engageable with one of said abutments to hold said brake in released position, means for placing said 130

latch into said abutment engaging position upon release of said brake, a manually operable lever engageable with another of said brake abutments to move said brake into released position and engageable with said latch to disengage said latch from said first mentioned brake abutment, and other means for automatically disengaging said latch from said first mentioned brake abutment at a predetermined time. 10
In testimony whereof, the signature of the inventor is affixed hereto.

OSWALD H. HANSEN.
